UNITED STATES PATENT OFFICE.

LAWRENCE LANDON SMART, OF YONKERS, NEW YORK, ASSIGNOR TO PARAMOUNT RUBBER CONSOLIDATED INC., OF TUCKAHOE, NEW YORK, A CORPORATION OF DELAWARE.

HOLLOW RUBBER TOY.

Application filed April 18, 1925. Serial No. 24,090.

This invention relates to a hollow rubber toy which is counter-weighted so that it tends to hold its position and return thereto when tipped therefrom but may be readily rocked. The toy may for instance comprise a ball or other article adapted to roll to some extent on a surface, or some floating object, as a representation of an animal, or indeed any object of a generally rounded form.

The ultimate purpose of the invention is to provide such toy in a form which will accomplish the desired result and be durable in use and yet is adapted for economical manufacture. More specifically, the invention provides an effective counter-weight which may be manufactured separate from the body and is provided with means so that it may be attached to the wall of the body and thereby fixedly mounted within it. The attaching means, which passes through the wall of the body, clamps the counter-weight in place in such manner that there need be no leakage by reason of the attachment, and furthermore, the outer member of the attaching device is arranged to lie within a depression of the rubber body so that it will not mar a surface on which the toy stands. By manufacturing the counter-weight first and placing it within the body of the article as the latter is being formed, I provide for economical manufacture of each part of the article, as hereinafter more fully explained.

If desired, the counter-weight may carry a suitable voice device, enabling the production of sound when the body is collapsed and expands. By mounting this voice device within the attaching means of the counter-weight it is effectively protected against injury, notwithstanding rough usage of the toy.

The drawings disclose two embodiments of my invention. Fig. 1 is an elevation of a hollow ball containing the counter-weight; Fig. 2 is a vertical section thereof on the line 2—2 of Fig. 1; Fig. 3 is a cross-section on the line 3—3 of Fig. 2. In this embodiment there is present a voice device carried by the counter-weight; Fig. 4 is a cross-section illustrating the counter-weight carried in a

hollow rubber object representing a duck; Fig. 5 is a cross-section on the line 5—5 of Fig. 4.

As shown in Figs. 1 and 2, A indicates a hollow approximately spherical body, made of rubber. Within the hollow body is a counter-weight C which may be made of any suitable material as wood, rubber, metal, etc. The counter-weight is held in place within the rubber body by a screw and nut couple, one member of which is embedded in the counter-weight, and the other member of which is on the outside of the rubber body, the screw passing through the rubber wall, which is thus effectively clamped by the external member against the counter-weight. As shown in Fig. 2, the screw D is the member embedded in the counter-weight, while the nut E is external and screws onto the threaded shank of the screw. The screw in this case is a bushing having external ribs or flanges d causing it to interlock effectively with the counter-weight.

The embodiment shown in Fig. 2 provides a bore within the bushing D which communicates with the interior of the hollow rubber body by a passageway d', and with external atmosphere by a passageway e in the nut. Within this bore, I place a suitable voice device F which is shown as comprising a suitable reed carried by a tubular body slidably mounted in the bore of the bushing.

In the construction just described, whenever the body of the article is collapsed, air is forced out through the voice device, and, as the body resumes its normal position due to the resiliency of the rubber, the air returns through this passageway. On the discharge or influx of the air, or both, the reed emits sound.

In Figs. 4 and 5, I have shown the hollow rubber body as comprising a duck B, which is intended to indicate a floating object. The counter-weight C in this case is held by a screw and nut couple partly internal and partly external, but, as the voice is omitted, I am able to simplify the construction. I accomplish this by making the nut G in the form of an internally threaded bushing mounted in the counter-weight while the

screw H has an external head L adapted to clamp the rubber between itself and the counter-weight.

In each of the embodiments shown, the counter weight is effective to return the body to the normal position shown when tipped therefrom, but does not interfere with the body being rocked or rolled to a certain extent, but causes it to eventually assume the upright position appropriate to the representation formed by the body or indicated on it.

It will be seen from inspection of Figs. 2 and 4, that in either case the rubber of the body is tightly clamped between the counter-weight and the external member of the clamping device, thus preventing leakage of air or water between these parts. Furthermore, it will be seen that such external member of the clamping device is mounted within a recessed portion a' or b' of the rubber wall, due to the shape of the counter-weight. The result is that the rubber wall is bent around the counter-weight and then in another direction across the clamping head, thus insuring a tight connection. Also the article is caused to rest on an annular portion of the rubber wall immediately surrounding the recess and extending below the clamping device, and there is no danger of the clamping device marring a table, for instance, on which the article stands.

I may very readily manufacture the article by employing such a process as set out in Reissue Patent No. 14,603 to Fred Thomas Roberts, wherein sheets of rubber are placed across cavitary molds and are seated therein by suction after which the molds are brought together and cutting edges thereon, surrounding the cavities, coact to form a seam between two sheets of rubber and at the same time cut off the surplus rubber outside of the seam.

In making the article shown, by the Roberts process, I first make the counter-weight and its member of the clamping device by suitable means, varying with the substance of the counter-weight. If the counter-weight is hard rubber for instance, a suitable amount of it is placed around the bushing and semi-cured thereon. Now, after the sheet rubber stock has been seated in the mold cavities by the Roberts process, I put one of these prepared counter-weights loosely in the lower rubber lined cavity and close the mold. This forms the body of the article, after which it is vulcanized in a suitable mold, thus producing a body, with protuberances or smooth as desired, and with the upwardly extending recess in the lower portion thereof.

I now cut a suitable opening through the wall of the body at the center of the recessed portion. This releases the internal pres-

sure, which was generated during vulcanization in the usual manner, and allows the body to be collapsed. By collapsing it, I can readily work the counter-weight manually into position where its bushing registers with the opening through the wall, and the other member of the attaching device is applied.

If the form shown in Fig. 2 is employed, the projecting bushing is passed through the rubber wall, then the voice device is inserted in the bushing, and then the nut is screwed onto the bushing and turned tightly into place, clamping the rubber against the counter-weight, and holding the voice device housed within the bushing, by which it is effectively protected. With the form shown in Fig. 4, when the bushing is brought into registration with the opening through the rubber, the screw is passed through the rubber and turned tightly into place, its head thus clamping the rubber against the counter weight.

It will be seen that by making the counter-weight separate from the wall of the body and clamping it in place after the body is independently formed, I am enabled to manufacture the body in a very economical and rapid manner from sheet rubber stock, and the counterweight, whatever its specific form, does not interfere with carrying out such economical method of manufacture as described.

Having thus described my invention, I claim:

1. The combination of a hollow rubber body, a counter-weight within the body, and a screw and nut couple for clamping the counter-weight to the body, one member of the couple being mounted in the counter-weight, the other member being adjacent the outside of the body, one member passing through the wall of the body, and coacting with the other member.

2. The combination of a hollow rubber body, a counter-weight within the same, a bushing within the counter-weight protruding through the body, an external clamping member coacting with the bushing and adapted to clamp the rubber of the body against the counter-weight, and a voice device within the bore of the bushing.

3. The combination of a hollow rubber body, a counter-weight within the same, a bushing within the counter-weight having a projecting portion with an external thread, an external clamping nut screwed on said thread and adapted to clamp the rubber of the body against the counter-weight, and a voice device within the bore of the bushing protruding through said body.

4. The combination of a hollow rubber body, a counter-weight within the same, a bushing within the counter-weight having

a portion projecting through the body and provided with a thread, a clamping nut outside of the body engaging said thread and adapted to clamp the rubber of the body 5 against the counter-weight, and a voice device within the bore of the bushing, said nut overhanging the bore of the bushing confining the device within the bushing, there being a passageway through the nut 10 into the interior.

5. The combination of a hollow rubber body, a counter-weight within the same, a bushing within the counter-weight protruding through the body, an external clamping member secured to said bushing and adapted to clamp the rubber of the body against the counter-weight, and a voice device within the bore of the bushing, the bushing being formed with an inward flange 20 overhanging the bore to position the voice device.

6. The combination of a hollow rubber body, a counter-weight within the same, a bushing within the counter-weight having a projecting portion protruding through the body and an external thread, an external clamping nut engaging said thread and adapted to clamp the rubber of the body against the counter-weight, and a voice device 25 within the bore of the bushing, the bushing being formed with an inward flange overhanging the inner end of the bore, and the nut overhanging the outer end of the bore, whereby the voice device is confined 30 within the bushing, there being a passageway for air through the nut and through the inner end of the bushing.

7. A counter-weight adapted to be mounted in a hollow rubber body and comprising a weight having a rounded bottom and a central recess within the bottom, and a fastening device comprising a screw and nut couple, one member of which is embedded 40 in the counter-weight directly above the recess, and the other member of which is adapted to lie against the exterior of the hollow rubber body, in cooperative relation with the first member through an aperture in the rubber body.

50 8. The combination of a hollow rubber body having an aperture therein, a counter-weight within the body, a bushing carried by the counter-weight, a clamping member on the outside of the body, and means connecting the clamping member with the bushing through said aperture, whereby the rubber wall may be forced against the counter-weight.

9. The combination of a hollow rubber body having an aperture therein, a counter-weight within the body, a bushing mounted in the counter-weight, a clamping member at least part of which is on the outside of the body, said clamping member having a threaded engagement with the bushing

through said aperture, and thus adapted to force the rubber wall against the counter-weight.

10. The combination of a counter-weight having a recess on its lower face, and a 70 hollow rubber body having an aperture therein enclosing the counter-weight and having its wall adjacent said aperture deflected into the recess, a member mounted in the counterweight adjacent the recess, a 75 second member disposed within the recess and externally of said wall and means for interlocking the members through said aperture.

11. The combination of a counter-weight 80 having a recess on its lower face, a hollow rubber body having an aperture therein enclosing the counter-weight and having its wall deflected into the recess, and a clamping device extending through said aperture 85 carried partly externally and within the rubber-lined recess, for holding the counter-weight in fixed relation to the body.

12. An article of the class described, comprising a hollow rubber body having an 90 aperture therein, a counter-weight therein made independently of the body, a threaded bushing carried by the counter-weight, the counter-weight having a recess on its lower face, a clamping member external of the 95 body within the recess and formed to engage the threads of the bushing, said clamping member and bushing cooperating through said aperture to clamp the rubber in the recess against the counter-weight. 100

13. The combination of a hollow rubber body having an aperture therein, a counter-weight within the same having a recess in its lower face, a clamping device adapted to force the rubber in the recess against the 105 wall of the counter-weight, said clamping device operating through said aperture and having its external member housed entirely within the rubber lined recess, the rubber wall extending below the lowermost point of 110 the clamping device.

14. The combination of a hollow rubber body having an aperture therein, a counter-weight within the same having a recess on its under-face, the wall of the body being 115 deflected into the recess, a bushing mounted in the counter-weight, an external clamping member housed entirely within the recess entirely above the bottom plane thereof co-operating with the bushing through said 120 aperture, said clamping device having a threaded engagement with the bushing.

15. The combination of a hollow rubber body having an aperture therein, a counter-weight disposed within the body, a clamp 125 for holding the counter-weight in place extending through the counter-weight and through the aperture in the body and a voice device carried by the clamp.

16. A counter-weight adapted to be mount- 130

ed within a hollow rubber body having an aperture therein and comprising a weight rounded and recessed on its underside and means associated with said weight for 5 clamping it in place, said means comprising a screw and nut couple, one member of which is carried by the weight, and the other member is disposed within the recess and co-operating with the first member through the 10 aperture in the body.

17. A counter-weight adapted to be mounted in a hollow rubber body having an aperture therein and comprising a weight having a recess therein and a screw and nut clamping device which device operates through said aperture, one member being embedded in the weight, and the other disposed within the recess. 15

18. A counter-weight applicable to the 20 interior of a hollow rubber toy, said toy comprising a rubber body having an aperture

therein, said counter-weight having a recess in its bottom, an attaching device including two members, one member disposed adjacent said recess, the other member disposed within the recess, and means for interlocking said members in clamping relation through said aperture. 25

19. A counter-weight adapted to be mounted in a hollow rubber body having an aperture therein, said counter-weight having a rounded bottom and an inwardly extending central recess, a fastening device being carried by the counter-weight directly above the recess comprising a member projecting through said aperture into said recess, and a second member of the fastening device disposed within the recess and in clamping engagement with the first member. 30

35 In testimony whereof, I hereunto affix my signature.

L. LANDON SMART.
